Primary Examiner — Cathron C Brooks*Assistant Examiner* — Christian P. McLean(74) Attorney, Agent, or Firm — Parks IP Law LLC(57) CLAIM

We claim the ornamental design for a bottle, as shown and described.

DESCRIPTION

FIG. 1 is a right view of a bottle in accordance with our new design;

FIG. 2 is a left view thereof;

FIG. 3 is a front view thereof;

FIG. 4 is a back view thereof;

FIG. 5 is a top view thereof; and,

FIG. 6 is a bottom view thereof.

The broken lines in the drawings illustrate the portions of the bottle that form no part of the claimed design.
